CLAIM

The ornamental design for a suction nozzle for cleaning machine as shown and described.

DESCRIPTION

1. Suction nozzle for cleaning machine

1.1 : Front top right perspective view

1.2 : Right

1.3 : Top left perspective view

1.4 : Front

1.5 : Back

1.6 : Top

1.7 : Bottom

The article of the design is a suction nozzle for cleaning machine that removes a contaminant, e.g., dirt, rust, paint, etc., from metal or concrete surfaces by high energy light pulses, and is used primarily in factories and construction sites; the broken lines showing in 1.1-1.7 are for the purpose of illustrating portions of the suction nozzle for cleaning machine that form no part of the claimed design.
